UNITED STATES PATENT OFFICE

161,690

POWER LAWN MOWER

Henry L. Heineke, Springfield, Ill.

Application April 19, 1950, Serial No. 9,320

Term of patent 14 years

(Cl. D40—1)

To all whom it may concern:

Be it known that I, Henry L. Heineke, a citizen of the United States, residing at Springfield, in the county of Sangamon and State of Illinois, have invented a new, original, and ornamental Design for a Power Lawn Mower, of which the following is a specification, reference being had to the accompanying drawing, forming a part thereof.

Fig. 1 is a front view of a power lawn mower, showing my new design;

Fig. 2 is a rear view thereof;

Fig. 3 is a perspective view taken from above and to one side of the power lawn mower, showing my design;

Fig. 4 is a left front perspective view; and

Fig. 5 is a view of my design looking down from directly above.

The characteristic features of the design reside in the portions shown in full lines.

I claim:

The ornamental design for a power lawn mower, substantially as shown and described.

HENRY L. HEINEKE.
